[57] ABSTRACT

An infra-red radiant heater comprises a combustion chamber defined by two oppositely-directed frustoconical members joined together at their bases. A burner is supported by one of the members and the other member has radial corrugations, this latter member being heated by the combustion gases and serving as an emitter of infra-red radiation. The corrugations direct the combustion gases towards a vent.

RADIANT HEATERS

FIELD OF THE INVENTION

The present invention relates to infra-red radiant heaters.

SUMMARY OF THE INVENTION

According to the present invention, there is provided in an infra-red radiant heater, a burner, two generally frusto-conical members facing in opposite directions and joined together at their bases, said frusto-conical members defining a combustion chamber, and vent means, one of said frusto-conical members supporting the burner, and the other frusto-conical member having corrugations arranged to direct the combustion gases towards the vent means.

The burner can be fed with liquid or gaseous fuel. When the heater is in action, the combustion gases play upon the said other frusto-conical member, the wall of which constitutes a heat-exchange surface and constitutes an emitter of infra-red radiation.

BRIEF DESCRIPTION OF THE DRAWINGS

An embodiment of the invention will now be described, by way of example only, with reference to the accompanying diagrammatic drawings, in which:

FIG. 1 is a longitudinal section of a heater in accordance with the invention; and

FIG. 2 is a transverse section of the heater taken at two different levels.

DESCRIPTION OF THE PREFERRED EMBODIMENT

The radiant heater shown in the drawing comprises a combustion chamber 1 defined by lower and upper frusto-conical members 2 and 7 facing in opposite directions and joined together at their bases.

The lower member 2 has radial corrugations 3 the dimensions and pitch of the corrugations increasing towards the base of the member 2. The corrugations 3 are of channel section having divergent walls.

A profiled lining wall 4 is welded within each corrugation and extends along part of the length thereof, the walls 4 defining with the corrugations 3, radial passages 21 for directing the combustion gases; these passages constitute a convector for effecting heat-exchange between the gases and the walls of the lower member 2.

The lower member 2 is welded by its base to an annular collector 5 the underside of which contains holes 6, equal in number to the corrugations in the lower member 2; each of the holes 6 in the collector 5 lies opposite one of the radial passages 21 in the lower member 2.

The upper member 7 is likewise welded at its base to the collector 5. The wall of the member 7 incorporates a number of concentric ridges 8 to strengthen it against deformation and the inner face of the member 7 is lined with a layer of non-rigid refractory material 9.

The combustion-chamber assembly thus formed is fixed by means of a detachable flange 14 to a circular plate 15. A metal reflector 16, having a highly polished inner face, is mounted on the periphery of the plate 15 and constitutes the reflector of the heater.

In its central portion the plate 15 has an opening over which is arranged the combustion tube 22 of a burner

17. A fan of the burner 22 is mounted on a door 18 which is attached by hinges 19 to the plate 15. By opening the door 18 the burner fan is displaced to give access to the combustion system located in the combustion tube. A fuel oil pump 20, for feeding liquid fuel to the burner, is coupled to the fan motor shaft.

The infra-red radiant heater described operates as follows:

When the burner 17 is in operation, the flame leaving the combustion tube 22 passes into the combustion chamber 1 of the heater. The high-temperature combustion gases pass downwardly in the chamber 1 and arrive at the inner surface of the lower member 2. The gases then pass upwardly through the passages 21 towards the base of the member 2; the gases enter the collector 5 via the holes 6 and are discharged to atmosphere through a pipe 10.

The flame serves to heat the lower member 2 by radiation and also by convection through the radial passages 21, through which the combustion gases pass. Further, radiant heat transmitted to the upper members 7 is reflected by the refractory lining 9 to the lower member 2, so that practically the whole of the heat content of the flame is transmitted to the lower member 2.

The wall of the member 2 is thus raised to a high temperature and the amount of infra-red radiation produced is governed by that temperature. The relatively small amount of radiant heat emitted from the upper cone is reflected by the reflector 16 over an angle of about 140°.

The radial corrugations 3 in the lower member 2 determine the path of the combustion gases in the combustion chamber, and also facilitate the emission of the infra-red radiation. When the lower member is raised to a high temperature by natural convection, a fraction of the heat is absorbed by the surrounding air, the result of this being a natural circulation of air around the member 2. The hollows of the corrugations, not being swept by that air circulation, are consequently less cooled, whereby the temperature of the member 2 is higher. By virtue of these corrugations, the loss of heat by natural convection is reduced by more than 50 percent, so that the emission of infra-red radiation is increased by about 80 to 85 percent.

In the heater particularly described high-intensity infra-red radiant energy can be transmitted to a long distance away with the result that the heater is particularly useful for heating large industrial or commercial premises such as, for example, stock-yards or swimming-pools and, in general, places where heating cannot be provided by hot-air convection.

What is claimed is:

1. In an infra-red radiant heater, a burner, two generally frusto-conical members facing in opposite directions and joined together at their bases, said frusto-conical members defining a combustion chamber, and vent means, one of said frusto-conical members supporting the burner, and the other frusto-conical member having corrugations arranged to direct the combustion gases towards the vent means.
2. A heater as claimed in claim 1, in which the corrugations are of channel section having divergent walls.

3. A heater as claimed in claim 1, further comprising

wall means closing each corrugation for at least part of its length, said wall means defining with the corrugation a radial circulation passage communicating with the vent means.

5

4. A heater as claimed in claim 1, further comprising

annular collector means, said collector means joining together the said frusto-conical members and being connected to the vent means, and said collector means having holes opposite the corrugations in the said other of the frusto-conical members.
